UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

CARLINE AND METHOD OF MANUFACTURE.

No. 836,371.

Specification of Letters Patent.

Patented Nov. 20, 1906.

Application filed May 17, 1905. Serial No. 260,810.

To all whom it may concern:

Be it known that I, ETHAN I. DODDS, a citizen of the United States, residing at Pullman, in the county of Cook and State of Illinois, have invented certain new and useful Improvements in Carlines and the Methods of Manufacture, of which the following is a specification.

My invention relates to carlines for rail-way-cars and the methods of making them, and pertains more particularly to that class of carlines which are made of pressed steel.

The object of my invention is to provide an improved carline combining the maximum of strength and rigidity with a minimum of cost and increased simplicity of manufacture.

Another object of the invention is to provide a carline which can readily be made by pressing the same from a commercial form of rolled beam, such as a channel-beam.

A carline constructed in accordance with my invention is illustrated in the accompanying drawings, wherein—

Figure 1 is an end view of a channel-beam from which my improved carline is preferably formed. Fig. 2 is a side elevational view of a longitudinal half of my improved carline. Fig. 3 is a top plan view of Fig. 2. Fig. 4 is a cross-sectional view, on an enlarged scale, at the longitudinal center of the carline; and Fig. 5 is a side elevational view, on a reduced scale, of the complete carline.

In constructing my improved carline I preferably start with a section of channel-beam A of a suitable length to extend from plate to plate of the car. This beam is subjected to compression between suitably-formed die members, whereby its web is pressed upwardly to form a hollow body, while its flanges are at the same time drawn into a common horizontal plane on either side of said outwardly-bent body portion. In order to secure the low sloping form requisite for the upper edge of the carline, the displacement of the web is greatest at the center, where consequently the body has its highest and narrowest formation, as shown at B, the body tapering with a gradual decrease in height and increase in width from the center to the ends, the downwardly-sloping upper surface of the body being represented by C and the warped sides by D. The two sides of the channel-beam are pressed

into the common horizontal plane of the lower horizontal edge of the outwardly-pressed body, thus forming lateral flanges E, that secure the necessary lateral rigidity of the member.

The upper surface C of the body member is preferably provided at intervals with seats for the purlins, which seats may be formed by cutting out the metal, as indicated at F, or by simply depressing it, as indicated at G. Either or both forms of seats may be employed in the same structure.

The flanges E may be formed with suitable bolt-receiving holes H opposite the purlin-seats to receive bolts uniting the purlins to the carlines.

By the use of suitable dies a carline of the described form may be readily pressed by a single operation from a commercially-rolled channel-beam, thus reducing the labor and expense of manufacture of this element of a car structure to a minimum. At the same time the disposition of the metal resulting from the pressing operation is such as to afford a rigid member well adapted to resist transverse strains in any direction.

I claim—

1. The method of manufacturing a carline from a channel-bar which consists in pressing up its web along its longitudinal median line to form a hollow body, the flanges being bent to lie in a common plane on either side of the pressed-up web, substantially as described.

2. The method of manufacturing a carline from a channel-bar which consists in pressing up its web along its longitudinal median line to form a hollow body of gradually-decreasing height and increasing width from its center to both ends, substantially as described.

3. The method of manufacturing a carline from a channel-bar which consists in pressing up its web along its longitudinal median line to form a hollow body of gradually-decreasing height and increasing width from its center to both ends, and bending the flanges to lie in a common plane on either side of the lower edge of said body, substantially as described.

4. The method of manufacturing a carline from a channel-bar, which consists in pressing up its web along its longitudinal median line to form a hollow body of decreasing height from its center to both ends and bending the flanges of said channel-bar to lie in a

common plane on either side of the lower edge of said body, substantially as described.

5. A pressed-steel carline having a hollow body, said body being of gradually-decreasing height and increasing width from its center to both ends, substantially as described.

6. A pressed-steel carline having a hollow body said body being of gradually-decreasing

height and increasing width from its center to either end, said body having lateral flanges lying in a common plane on either side of its lower edge, substantially as described.

ETHAN I. DODDS.
